WELL DRILLING MACHINE

Harland W. Cardwell, Wichita, Kans., assignor to
 Cardwell Manufacturing Company, Inc., a corporation of Kansas

Application October 27, 1938, Serial No. 237,300

1 Claim. (Cl. 255—7)

This invention relates to well drilling machines and more particularly to a well drilling tractor in which all of the various mechanisms for cable tool drilling, spudding, sand line operation, and rotary drilling may be incorporated in a single power driven portable device. The invention contemplates a power driven portable well drilling machine which may be comparatively small and compact and in which the load on the tractor is so distributed as to provide a well balanced portable unit in the form of a tractor, and wherein the tractor and all of the various associated mechanisms may be operated from a single power source such as the usual tractor motor.

It is an object of the invention to provide a well drilling machine of the tractor type having a plurality of well drilling mechanisms associated therewith and in which all of the mechanisms may selectively be controlled for drilling operations; also in which these mechanisms are so positioned as to provide a well balanced unit and not materially interfere with the normal operation of the unit as a tractor.

The invention comprises a tractor structure which may be of the usual so-called track type or caterpillar type having a suitable framework or chassis for supporting the various well drilling mechanisms, the framework and mechanisms being so arranged that the so-called drilling drum on which the drilling cable is wound may be mounted substantially on the plane of the center of gravity of the tractor. This arrangement of drum mounting is very desirable in that the device ordinarily carries a full drum of drilling line which may weigh approximately 6,000 pounds, more or less, when used with cable drilling tools.

The various mechanisms on the tractor may be so positioned that the spudding attachment is in the rear of the drum, but closely associated therewith, and the sand line drum is at the rear of the spudding attachment and at the rear of the tractor. This enables the positioning of the tractor relative to the usual derrick so that the sand line cable and the drilling cable may both be operated inside the derrick, which is very desirable, particularly when using the spudding attachment.

In the operating position the tractor may be located with the well drilling mechanism within the derrick and the entire structure may be held down by means of a girt resting on the top of the framework of the machine and fastened to the derrick legs, or a header board may be provided across the top of the machine with the ends

chained down or otherwise secured to the corners of the derrick.

Another object is the provision of a tractor drilling machine in which the lighter mechanisms such as the clutches for controlling the drums are located adjacent the top of the structure, and the heavier mechanisms as low as possible, with the cable tool drum substantially on the plane of the center of gravity of the tractor, whereby a full drum of drilling cable may be carried without tipping hazard.

The invention also contemplates a well drilling unit in which both the drilling cable and the sand line may be controlled from inside the derrick. This is accomplished in the present embodiment by positioning the spudding sheave between the drums with the sand line drum at the rear of the machine.

Another object is to provide a combined rotary drilling, cable-tool drilling, and sand line operating device in the form of a comparatively small compact tractor unit preferably having a single power source and suitable controls.

A further object of the invention is the provision of a well drilling tractor of the character described in which all of the controls are within easy reach of the operator and in which any of the mechanisms may be controlled independently of other controls or concurrently therewith.

30 Further objects will be apparent from the specification and the appended claim.

In the drawings:

Fig. 1 is a front perspective view of one embodiment of the invention.

35 Fig. 2 is a rear perspective view of the embodiment illustrated in Fig. 1.

Fig. 3 is a somewhat diagrammatic top plan view of the embodiment illustrated in Figs. 1 and 2 with the cover and chain guards removed.

40 Fig. 4 is a side elevation of the well drilling mechanism and a portion of the framework on which it is supported.

Fig. 5 is a diagrammatic view of the well drilling mechanism and illustrates the manner in 45 which the various elements may be selectively controlled and driven from the prime mover of the tractor.

Referring to the drawings in detail, the embodiment illustrated comprises a tractor portion 50 having the usual chassis and a motor housing with the usual motor therein. The tractor may be of any suitable type, preferably of the caterpillar type, as shown, and provided with the usual caterpillar tracks 2. In other words, any suitable tractor structure may form the automotive

element of the invention. A suitable framework may be mounted on the tractor and secured thereto by any suitable means or may form a portion of the tractor chassis and may comprise a pair of spaced parallel beams 3 interconnected and transversely braced by any suitable means. A pair of upstanding angularly positioned beams 4 and 5 is supported on each side beam 3 and angularly arranged with respect to each other to form an inverted V with the upper ends of the beams suitably connected. The beam 5 extends upwardly beyond the apex of the V, whereby the upper ends 6 of these beams are positioned so that a girt or header board may be supported thereon or engaged thereby and the entire unit held down by fastening the girt to the legs of the usual derrick, or the header board may be chained down to the corners of the derrick. The V-shaped frames may be connected together at their upper ends by means of a transverse beam 7, whereby the structure just described forms a suitable rigid framework for supporting all of the well drilling mechanism.

All of the various shafts forming a part of the well drilling mechanism are mounted transversely on the framework and the entire mechanism and controls are shown diagrammatically in Fig. 5. All of the mechanism may be driven from the usual power take-off shaft 8. The take-off shaft may be provided with a sprocket 9 and connected in driving relation to a transverse main drive shaft 10 near the rear of the machine by means of a chain 13 and sprocket 14 secured on the shaft 10. The shaft 10, in turn, drives a stub shaft 15 leading therefrom through a variable speed transmission 16. This transmission is preferably an eight-speed transmission which may be controlled by means of any suitable shift lever connected to an operating link 17, which, in turn, controls the transmission. A countershaft 18 is mounted adjacent the apex of the V-shaped framework and is driven from the stub shaft 15 by means of a chain 19 and suitable sprockets 20 and 21 secured to the respective shafts, as shown.

A drilling-drum shaft 22 is mounted in suitable bearings on the beams 5 and as low on the framework as possible and substantially on the plane of the center of gravity of the tractor. A drilling cable drum 23 is rotatably mounted on the shaft 22 and provided with a sprocket 24 secured thereto which may be driven from the countershaft 18 by means of a chain 25 and a sprocket 26 rotatably mounted on the countershaft. The sprocket 26 forms the driven member of a friction clutch 27, the driving portion of which is secured to the shaft 18, and this clutch may be controlled by means of a link 28 suitably connected for operating the clutch to connect or release the driving transmission to the drum. The link 28 may, of course, be operated by means of any suitable control handle or lever connected thereto, all of the controls being assembled adjacent the operator's position on the machine.

It will be apparent that, with the mechanism just described, the operator may control the speed of the countershaft 18 by proper manipulation of the link 17 controlling the reverse and variable speed transmission 16, and manipulation of the link 28 will cause the driving transmission leading to the cable drum 23 to be connected or disconnected as desired. The shaft 21 on which the cable drum is mounted need not necessarily

be rotatable. The drum may rotate on a fixed shaft if desired.

A spudding attachment is provided for the drilling cable and is closely adjacent the cable drum as illustrated in Fig. 4. This spudding attachment is preferably somewhat similar to that illustrated in my prior patent, Reissue 20,454, July 27, 1937, and may comprise a cable sheave 29 rotatably and slidably mounted on a shaft 30, which is, in turn, supported on arms 31 secured to an oscillatable shaft 32. The sheave shaft 30 may be adjusted to vary the tool stroke by positioning it in appropriate supporting pockets 31a on the arms 31. The oscillating shaft 32 is mounted in suitable bearings on the frame and provided with a spudder arm 33 secured thereto and having a slot 34 therein as shown in Figs. 1, 2, and 4. A sprocket 35 is rotatably mounted on the cable drum shaft 22 and provided with an outwardly extending crank pin in the form of a roller 36, which is engaged in the slot 34 in the spudder arm. The sprocket 35 may be driven from the countershaft 18 by means of a sprocket 37 rotatably mounted thereon and a driving chain 38. The sprocket 37 forms the driven member of a jaw clutch 39, which clutch may be controlled by means of a link 40 which may be provided with a suitable operating handle adjacent the operator's position. When the clutch 39 is engaged, the sprocket 35 on the cable drum shaft will be rotated and the spudder arm and spudder sheave connected thereto will be oscillated to perform the usual spudding operation.

The slot 34 of the spudding arm is preferably shaped substantially as illustrated in Fig. 4 to provide a brief dwell of the spudding sheave 29 during a portion of its cycle. This dwell takes place when the spudding sheave is in its raised position; that is, when the drilling tool is dropped into the hole. By providing a dwell at this point instead of promptly starting the sheave on its downward stroke to raise the tool, time is permitted for the stretch to get out of the cable so that it is taut at the end of its downward stroke and the tool thereon is permitted to strike a more powerful blow. Thus, if the dwell were not provided, the tool might be picked up before it had been permitted time to deliver an efficient blow.

In order to provide an efficient assembly and to enable positioning all of the parts compactly with the cable drum substantially on the plane of the center of gravity of the tractor, the countershaft 18 and the clutch mechanism thereon are positioned substantially at the apex of the framework and above the cable drum and spudding attachment.

A cathead shaft 41 is mounted in suitable bearings at the rear of the framework, as shown, and in closest proximity to the drill pipe to be broken out or made up, and provided with suitable catheads 42 secured on each projecting end of the shaft. A sand line drum 43 is rotatably mounted on the cathead shaft, whereby a suitable sand line may be operated in the usual manner. The shaft 41 is also provided with a suitable sprocket 44 secured thereto and may be driven from a friction clutch 45 on the countershaft 18 by means of a sprocket chain 46 and a suitable sprocket forming a part of the driven member of the clutch 45.

The driving member of the clutch may be controlled by means of a link 47, which link may be provided with a suitable handle adjacent the operator's position. By this means, the sand line drum may be operated at any desired time by

manipulation of the link 47 controlling the clutch 45.

Means is also provided for driving the rotary table of a rotary drilling device such as shown diagrammatically in Fig. 5. The drilling device may comprise the usual rotary table 48 which is driven by means of a shaft 49 having a bevel pinion 50 thereon and in mesh with a suitable bevel gear on the rotary table. The shaft 49 is provided with a sprocket 51 whereby the table may be driven from a sprocket 52 loosely mounted on the stub shaft 15 and connected to the sprocket 51 by means of a chain 53. The sprocket 52 forms the driven member of a jaw clutch 54, which clutch may be controlled by means of a link 55 in the same manner as the control links previously described.

Any one or all of the various mechanisms may be driven at a desired speed or reversed by manipulation of the link 17 controlling the variable transmission 16 and all of the mechanisms may be driven from the usual take-off power shaft of the prime mover of the tractor.

A platform 56 is provided on one side of the tractor unit and a seat 57 for the operator may be mounted thereon. The platform may be secured to the side of the chassis, as shown immediately above one of the tracks. All of the various control levers and handles for controlling the motor may be mounted as shown within easy reach of the operator. Also, control handles or levers for the various well drilling elements are mounted adjacent the operator's seat and suitably connected to the control links. It is believed to be unnecessary to describe these control elements in greater detail. A removable cover 58 may be provided for the drilling line drum, and various chain guards or guards for other parts of the mechanism may be applied in any suitable manner such as shown in Fig. 2.

Friction clutches are preferably used for controlling the drilling drum and sand line drum and are particularly advantageous in providing accurate control of the drums and obviating the necessity of stopping the mechanism from the prime mover end in order to engage or disengage the clutches, which is necessary every time the drill pipe is raised, and it is very often necessary to raise the drill pipe every few minutes in order to keep the proper weight on the pipe and prevent crooked hole drilling.

A very desirable feature of the invention is that the drilling line drum may be operated simultaneously with the rotary drilling table, which adds to drilling speed, and the friction clutches for controlling the drums relieve the

entire machine of shock which is always present when jaw clutches are used.

It will be understood, of course, that both the cable drilling drum and the sand line drum may have the usual manually controlled clutch associated therewith for permitting the drums to spin freely when lowering the traveling blocks or lowering the bailer into the hole; that is, a suitable clutch is provided between the sprocket 24 and the drilling line drum 23 and a similar clutch between the cathead shaft 41 and the sand line drum 43.

Modifications may be made without departing from the spirit of the invention, and it is therefore desired that the invention be limited only by the prior art and the scope of the appended claim.

Having thus described this invention, what is claimed and desired to be secured by Letters Patent is:

A portable well drilling machine comprising, a tractor with a prime mover at the front thereof, a frame thereon for supporting well drilling mechanisms and extending to the rear materially beyond the tread of said tractor whereby it may overhang the usual well platform when inserted within the usual derrick, a low hung transverse cathead shaft rotatably mounted adjacent the extreme rear end of said frame and terminating in catheads outside said frame, a sand line drum rotatably mounted on said shaft, manually operable means for clutching said sand line drum to said shaft, a transverse drill line drum adjacent the central transverse vertical plane of said tractor, both of said drums being closely adjacent the bottom of said frame, said frame including an upright portion forming a hold down means terminating between and a material distance above said drums, a countershaft on said upright and above said drill line drum and on the same side of said hold down as said drill line drum and having a driving connection with each of said drums, a manually operable friction clutch in each of said driving connections, a variable speed driving connection between said prime mover and said countershaft, a vertically and laterally movable spudder sheave between said drums and below said countershaft and arranged in any position of its movement to direct a drill line cable directly therefrom to the crown pulley of the usual derrick and at the rear of said hold down when said sand line drum is inserted within said derrick with the hold down adjacent the side frame thereof.

HARLAND W. CARDWELL.
